Fred Michael, Oelwein, Iowa

Application June 17, 1944, Serial No. 114,049

Term of patent 14 years

(Cl. D90—20)

To all whom it may concern:

Be it known that I, Fred Michael, a citizen of the United States, residing at Oelwein, in the county of Fayette and State of Iowa, have invented a new, original, and ornamental Design for an Automobile Tire, of which the following is a specification, reference being had to the accompanying drawing, forming part thereof.

Figure 1 is a side elevational view of a portion of an automobile tire showing my new design, Figure 2 is a top plan view, and Figure 3 is a cross sectional view thereof.

I claim:

The ornamental design for an automobile tire, as shown.

FRED MICHAEL.
